[57] CLAIM

The ornamental design for vertical holder for rolled paper products, as shown and described.

DESCRIPTION

FIG. 1 is a top, front perspective view of a vertical holder for rolled paper products showing my new design;

FIG. 2 is a front elevational view thereof, shown broken-away for convenience of illustration;

FIG. 3 is a rear elevational view thereof, shown broken-away for convenience of illustration;

FIG. 4 is a top plan view thereof;

FIG. 5 is a bottom plan view thereof;

FIG. 6 is a right side elevational view thereof, the left side being a mirror image;

FIG. 7 is a top, front perspective view of a second embodiment thereof;

FIG. 8 is a front elevational view of the embodiment of FIG. 7;

FIG. 9 is a rear elevational view of the embodiment of FIG. 7;

FIG. 10 is a top plan view of the embodiment of FIG. 7;

FIG. 11 is a bottom plan view of the embodiment of FIG. 7; and

FIG. 12 is a right side elevational view of the embodiment of FIG. 7, the left side being a mirror image.
